ATTY.

UNITED STATES PATENT OFFICE.

EDWARD BRUNS, OF PORTLAND, OREGON.

NO-GLARE HEADLIGHT.

1,217,912.

Specification of Letters Patent. Patented Mar. 6, 1917.

Application filed August 14, 1916. Serial No. 114,904.

To all whom it may concern:

Be it known that I, EDWARD BRUNS, a citizen of the United States, and a resident of the city of Portland, county of Multnomah, 5 State of Oregon, have invented a new and useful Improvement in No-Glare Headlights, of which the following is a specification.

This invention relates generally to the lenses of headlights of autos. As well 10 known, the common headlights project strong beams of light, thus producing a blinding glare which is both confusing and dangerous. For that reason traffic regulations require that headlights be dimmed, or 15 otherwise arranged to eliminate any glare.

The object of my invention is to break up and spread out, in short, to disperse the projected rays of the lamp in a lateral direction through the medium of the lens, in 20 this way using substantially the full illuminating power of the lamp, but avoiding all strong or blinding rays.

I attain my object by a lens the entire 25 surface of a portion of which is covered with narrow, contiguous, parallel ribs of prismatic cross section.

The details of construction of my lens and 30 the theory of its operation are hereinafter fully described and shown in the accompanying drawings, in which:

Figure 1 shows, in diagrammatic form, the housing of a headlight, understood to include a parabolic reflector, it also shows the lamp and a diagrammatic section of my lens 35 on the line 1—1 of Fig. 2;

Fig. 2 is a rear elevation of my lens, more or less diagrammatic, and as viewed when looking in the direction pointed by the arrow;

40 Fig. 3 is a partial section, drawn on an enlarged scale, along the line 3 of Fig. 2; and

Fig. 4 is an exaggerated diagrammatic cross-section showing more clearly the cross-sectional structure of said prismatic ribs.

45 *a* represents the lens in its entirety. The lens is of the convex-concave type and of a diameter suitable to the particular lamp for which it is to be used.

50 In Fig. 1, *b* represents a parabolic reflector of the usual type, and *c* is a lamp, or source of light, located at the focal center, the rays of the lamp being projected forward in a solid beam of parallel elements.

55 The lens is made of molded opalescent glass, the inner or concaved surface being

finished as follows: The portion *d* is ground or sanded so as to be merely translucent, instead of transparent. The entire surface of the portion *e* is covered with narrow, contiguous, parallel ribs as *f*, of prismatic cross-section, as diagrammatically illustrated in an exaggerated form in Fig. 4. The ribs are arranged perpendicular to an imaginary diameter dividing said translucent portion 60 from said rib portion of the lens. By reason of such construction the rays transmitted through the prismatic ribs are dispersed in a lateral direction, a large number of them being projected directly forward, and so the 65 whole space in front of the lens is illuminated effectively, very little of the illuminating power of the lamp being lost. But the illumination will be without any glare; indeed one may look directly at the light 70 from any point in front of the lens. The described result is due to the fact that some 75 of the rays will be projected directly forward, as indicated by the line *h*, others approximately as indicated by the line *i*, and the rays diagrammatically illustrated by *j*, *k* being given still other deflections, so that the whole volume of light will be evenly distributed.

In practice I have found that making the 80 ribbed surface *e* of the lens with said ribs running twenty to the inch brings about very satisfactory results. And I also deem it preferable that the prismatic ribs be made, as diagrammatically shown in Fig. 4, instead of having straight prismatic faces.

85 Preferably the defining line represented by *g*, between the translucent (*d*) and ribbed (*e*) surfaces of the lens, is symmetrically curved, so that its central portion extends 90 lower than and covers the source of light, and its side portions flare outwardly to points slightly above the horizontal diameter of the lens.

I prefer to make my lens of rolled white 100 flint glass. I have also found the best results are obtained by making the lens of a curvature similar to that shown in Fig. 1; *e. g.*, with a central portion—about one sixth of the diameter of the lens—of very 105 flat curvature, surrounded by a zone of a considerably sharper curvature which blends into a marginal zone of reverse curvature, the latter ending in an approximately flat surface to permit the lens to fit readily in 110 any standard automobile lamp. The radii of these zones of my lens are given in Fig. 1.

I claim:

1. In a headlight, the combination of a lamp, a hood therefor including a parabolic reflector and a lens covering the front of such hood, said lens having a portion of its surface translucent and the entire remaining portion of its surface covered with narrow, contiguous, parallel ribs of prismatic cross section and arranged perpendicular to an imaginary diameter dividing said translucent portion from said rib portion of the lens.
2. A convex-concave lens for a headlight having a portion of its surface translucent and the entire remaining portion of its surface covered with narrow, contiguous, parallel ribs of prismatic cross-section and arranged perpendicular to an imaginary diameter dividing said translucent portion from said rib portion of the lens.
3. A lens made with an approximately flat middle portion, being convex from such portion, a portion of the lens being covered with narrow, contiguous parallel ribs of prismatic cross section, said ribbed portion of the lens extending V form below the center of the lens.
4. A lens made with an approximately flat middle portion, being convex from such portion, a portion of the lens being covered with narrow, contiguous parallel ribs of prismatic cross section, said ribbed portion of the lens extending V form below the center of the lens, and the remaining portion of the lens being translucent.
5. A lens made with an approximately flat middle portion, being convex from such portion, and reversely curved at its margin, a

portion of the lens being covered with narrow, contiguous parallel ribs of prismatic cross section, and the remaining portion of the lens being translucent.

6. A lens made with an approximately flat middle portion, being convex from such portion, and reversely curved at its margin, a portion of the lens being covered with narrow, contiguous parallel ribs of prismatic cross section, said ribbed portion of the lens extending V form below the center of the lens, and the remaining portion of the lens being translucent.

7. A lens made with an approximately flat middle portion, being convex from such portion, and reversely curved at its margin, the latter terminating in a more or less flat surface; a portion of the lens being covered with narrow, contiguous parallel ribs of prismatic cross section, said ribbed portion of the lens extending V form below the center of the lens, and the remaining portion of the lens being translucent.

8. In a headlight, the combination of a lamp, a hood therefor including a parabolic reflector and a lens covering the front of such hood, said lens having the upper portion of its surface covered with vertical, narrow, contiguous, parallel ribs of prismatic cross-section, such ribbed portion having its central portion extending slightly lower than and covering the source of light and curving upwardly at the sides to points slightly above the horizontal diameter of the lens, and the entire remaining portion of its surface being translucent.

EDWARD BRUNS.
